UNITED STATES PATENT OFFICE.

HENRY M. VINSON, OF THORNTON, TEXAS.

DESIGN FOR A CLOTHES-LINE SECTION.

SPECIFICATION forming part of Design No. 33,133, dated August 28, 1900.

Application filed July 5, 1900. Serial No. 22,644. Term of patent 7 years.

To all whom it may concern:

Be it known that I, HENRY M. VINSON, a citizen of the United States, residing at Thornton, in the county of Limestone and State of Texas, have invented and produced a certain new and original Design for a Clothes-Line Section; and I do declare the following to be a full, clear, and exact description of the invention, such as will enable others skilled in the art to which it appertains to make and use the same.

The invention relates to a new and original design for a clothes-line section; and it consists of a design of the shape and configuration shown in the accompanying drawings, in which—

Figure 1 is a side elevation of the clothes-line section, and Fig. 2 is a top plan view.

The leading feature of the design consists of two strands having twists at *a b*, divergent at points *c d* and angular in opposite directions at the points *e* and *f*, forming diamonds *g* and tapering slits *h*.

What I claim is—

The design for a clothes-line section as herein shown and described.

In testimony whereof I have hereunto set my hand in presence of two subscribing witnesses.

HENRY M. VINSON.

Witnesses:

E. B. CLOUNCH,
M. B. HODGES.
